RADIOCIRCUIT

Lester L. Jones, Oradell, N. J., and Jacob Yolles, Brooklyn, N. Y., assignors to Technidyne Corporation, New York, N. Y., a corporation of New York

Application October 29, 1929, Serial No. 403,161

23 Claims. (Cl. 179—171)

This invention relates to radio circuits and more particularly to such circuits including amplifiers having fixed circuit constants.

In a patent to Lester L. Jones No. 1,673,287, issued June 12, 1928, he discloses how a vacuum tube amplifier stage may have fixed output and input circuits so relatively adjusted that the output circuit serves to keep the input circuit of the tube in tune with the frequency of energy being sent through the amplifier. The output circuit there disclosed works into a detector tube which, owing to the output circuit thereof being shunted for radio frequencies, has a small fixed input capacitance with respect to radio frequency energy. This permits the output circuit of the automatically tuned stage to be kept resonant to a fixed frequency lower than the working range of frequency, as is desirable for automatically tuning the input circuit of the amplifier stage.

If it be desired to have a plurality of similar amplifier stages arranged in cascade it is not feasible merely to cascade such stages directly together because, for example, the input circuit of the last stage, which acts as the output circuit of the next to the last stage, instead of remaining resonant to a constant low frequency, is kept in tune with the working frequency and therefore is not suitable for automatically tuning the input circuit of the next to the last stage. In a co-pending application of Lester L. Jones, Serial No. 397,633, filed Oct. 5, 1929, since issued as Patent 1,779,881, dated October 28, 1930, he has explained how a plurality of automatically tuned stages may be cascaded directly together by arranging each of the stages to tune over different portions of the frequency range and cascading the stages directly together in the order of decreasing frequency.

This arrangement has an advantage when dealing with a broad frequency range because it is difficult to provide a stage which will tune automatically over a very broad frequency range while employing ordinary tubes. However, it is not desirable to intentionally subdivide the frequency range into a greater number of frequency portions than is necessary to cover the desired range merely in order to cascade a greater number of amplifier tubes.

The primary object of the present invention is to make possible the use of any desired number of automatically tuned stages regardless of the breadth of the frequency range and regardless of the frequency range to which any one stage is capable of tuning. For this purpose we have found it possible to provide between two auto-

matically tuned amplifiers a special form of coupling stage, which, for the sake of convenience and brevity, we shall herein refer to as a "link stage" or "link circuit". Such a link stage may and preferably does include a tube having at all times a constant apparent input capacitance, into which capacitance the first or preceding automatically tuned amplifier works. This constant capacitance makes it possible for the input circuit of the link stage, which operates also as the output circuit of the first amplifier, to be made naturally resonant to a constant frequency lower than the desired range of frequency, which is the most favorable condition for automatically tuning the first amplifier. By the use of such link stages, if a single automatically tuned stage is capable of covering the desired frequency range and a powerful amplifier is needed, it is merely necessary to cascade automatically tuned stages and link stages in alternation. If the frequency range is broad a plurality of automatically tuned stages may be cascaded directly together to form a single automatically tuned amplifier capable of covering the desired frequency range, in accordance with the teachings of the copending application Serial No. 397,633, since issued as Patent 1,779,881, aforesaid, and, if a more powerful amplifier is needed, it is merely necessary to employ link stages for coupling several such complete amplifiers in cascade.

A further object of our invention resides in the provision of a suitable arrangement or circuit to act as the so-called link circuit or link stage for the foregoing purpose. This may be done with an ordinary tube by so designing the output circuit of the tube as to prevent reaction upon the input circuit of the tube and to obtain a small constant apparent input capacitance for the tube. It may also be accomplished by the use of a special tube such as the screened grid tube, in which the constant desired input capacitance is obtained by reason of a fourth electrode which shields the control electrode from the anode of the tube.

A still further object of the present invention resides in the provision of a complete receiver embodying the foregoing features of my invention, and further embodying a novel and relatively simplified link circuit for preventing reaction upon a sharply tuned pre-selector by an amplifier following the selector.

To the accomplishment of the foregoing and such other objects as will hereinafter appear, our invention consists in the circuit elements and their relation one to the other as hereinafter are

60

more particularly described in the specification and sought to be defined in the claims. The specification is accompanied by drawings in which:

- 5 Fig. 1 is a wiring diagram showing automatically tuned amplifier stages working into a detector tube;

Fig. 2 is a schematic diagram explanatory of our invention;

- 10 Fig. 3 is one form of link circuit which may be used between automatically tuned amplifiers;

Fig. 4 is an alternative form of link circuit which may be used between automatically tuned amplifiers;

- 15 Fig. 5 is a differently coupled form of link stage which may be used between automatically tuned amplifiers;

Fig. 6 is a schematic wiring diagram for a complete receiver embodying our invention;

- 20 Fig. 7 is a wiring diagram for a modified amplifier employing link stages similar to that in Fig. 3; and

Fig. 8 is a wiring diagram for another amplifier employing link stages such as are shown in Fig. 4.

- 25 Referring to Fig. 1, there is an amplifier tube 2 followed by a detector tube 4. The output circuit of the detector tube is provided with a filter section 6 for separating the radio frequency and modulation components of the received energy, 30 and this being a low impedance shunt for radio frequencies, causes the input circuit of detector tube 4 to have an apparent input capacitance for radio frequencies represented by the dotted condenser 8, which is constant and pure.

- 35 The amplifier tube 2 is provided with an input transformer 10 and an output transformer 12, both of which are preferably bifilarly wound so as to have substantially unity coupling. The transformer 12 is made naturally resonant in circuit 40 to a frequency lower than the lowest frequency of the working frequency range. For frequencies in the working frequency range the output circuit of tube 2 is therefore capacitive and decreases in impedance with increasing frequency, causing 45 decreasing apparent input capacitance with increasing frequency in tube 2, this capacitance being represented by the dotted variable condenser 14. Transformer 10 is selected to resonate with variable capacitance 14 for automatic tuning.

- 50 Variation of capacitance 14 is obtained because the output circuit of tube 2 remains naturally resonant to a low frequency, and this in turn is made possible by capacitance 8 remaining fixed. At 55 high frequencies transformer 12 departs from resonance and is low in impedance, which reduces the apparent input capacitance 14. The range of tuning may be increased in accordance with the teachings of our copending application Serial No. 402,378, filed October 25, 1929, since issued as 60 Patent 1,909,968, dated May 23, 1933, by the use of a series inductance section 16 so dimensioned as to series resonate with the input capacitance at the high frequency end of the range. The resulting shunt across transformer 12 still further reduces the impedance thereof at high frequencies and still further reduces the apparent input capacitance 14, and thereby increases the available range of automatic tuning. The gain at high frequencies is also increased by the resonant rise 65 in potential obtained across the capacitance 8 in the series resonant circuit.

- If amplifier tube 2 is preceded by another amplifier tube 20 it is not possible to make the tube 20 tune automatically over the same frequency range as the tube 2. This follows be- 70

cause the output circuit of tube 2, instead of being naturally resonant to a constant frequency lower than the frequency range, is resonant to a variable frequency and remains in tune with the received frequency. The resulting high impedance causes the apparent input capacitance of tube 20, represented by the dotted condenser 22, to remain high, and therefore is not suitable for automatically tuning the input circuit of tube 20. This stage differs from the stage including tube 2, the output circuit of which, corresponding to input circuit of the detector tube 4, remains naturally resonant to a constant frequency lower than the frequency range. In referring to the resonance frequency of the input circuit of detector tube 4 the frequency for parallel resonance is meant. The series resonance of inductance 16 and capacitance 8 at high frequencies is really equivalent to an increase in the departure of the circuit from parallel resonance at high frequencies, in that the series resonant shunt further reduces the impedance of transformer 12 at high frequencies. 80 85 90 95

In accordance with the disclosure of the co-pending application Serial No. 397,633, since issued as Patent 1,779,881, already referred to, the tubes 20 and 2 may be cascaded directly together when dealing with a broad range of frequency provided that tubes 2 and 20 are adjusted respectively to automatically tune over the lower frequency portion and the higher frequency portion of the frequency range, because the highest frequency to which the input circuit of tube 2 can then tune is an intermediate frequency, and for the still higher frequencies in the high frequency portion of the range the input circuit of tube 2, corresponding to the output circuit of tube 20, is resonant to a relatively lower frequency and therefore is suitable for automatic tuning. It then would not be possible to cascade a third automatically tuned stage ahead of the tube 20 unless the working frequency range were divided into three different frequency portions. However, it is not desirable to do so unless such a step proves necessary in order to cover the desired frequency range. 100 105 110 115 120

In accordance with the present invention an automatically tuned amplifier, such as the amplifier 30 in Fig. 2, which may consist of one or as many more stages as may be needed to cover the desired frequency range, may be preceded by another automatically tuned amplifier, 32, which may, if desired, be a similar amplifier arranged to cover the same frequency range, provided that the amplifiers 30 and 32 are coupled together by a special link such as the link 34, which in one aspect may be considered as being characterized by a fixed and perfectly pure apparent input capacitance, and which may be considered in another aspect, as having an input circuit which is naturally resonant to a constant frequency lower than the working frequency range. 125 130 135

Fig. 3 shows one form which the link stage may take. In Fig. 3 there is an electron emission tube 40, the output circuit of which is arranged in accordance with the disclosure in a patent to Lester L. Jones No. 1,713,132, issued May 14, 1929, which may further embody the improvements set forth in his copending application Serial No. 397,632, filed October 5, 1929, since issued as Patent 1,788,197, dated January 6, 1931. This output circuit consists essentially of an inductance 42 which in connected circuit is naturally resonant to a frequency higher than the working frequency range so that it is effectively inductive and regen- 140 145 150

erative in the working frequency range. Resistance 44 is selected to provide a feed forward of energy through tube 40 for neutralizing the feed back caused by inductance 42. The succeeding circuit may be coupled to the output circuit so far described by a transformer 46 arranged in parallel with the output circuit. Various changes may be made in this circuit, the effect of which is described in the said patent and copending application, but generally speaking, when the output circuit is properly arranged and proportioned the effect thereof is to prevent reaction through the tube 40 and to cause the tube to have an apparent input capacitance, indicated by the dotted condenser 48, which is substantially fixed. This permits the selection of an input transformer 50 which is naturally resonant in circuit to a frequency lower than the working frequency range. The conductance and capacitance values remaining constant, the resonance frequency will be fixed, as is desired for automatically tuning a preceding amplifier stage.

In Fig. 4 we have illustrated a different form of link circuit in which a screened grid vacuum tube 52 is employed, having in its output circuit a transformer 54, selected as the desired transformer for a succeeding automatically tuned amplifier. The control electrode and anode of the tube are separated or shielded by a screen 53, and the apparent input capacitance of the tube, represented by the dotted condenser 56, is therefore fixed, and consequently a bifilar wound input transformer 58 may be selected which will be naturally resonant in circuit to a constant frequency lower than the working frequency range, suitable for the output circuit of a preceding automatically tuned amplifier stage.

In Fig. 5 we have illustrated a very similar form of link circuit in which, however, a form of impedance coupling rather than transformer coupling is used. As in the link circuit shown in Fig. 4, there is a screened grid vacuum tube 252 having in its output circuit a transformer 254 selected as the desired transformer for a succeeding automatically tuned amplifier. The control electrode and anode of the tube are separated or shielded by a screen 253 and the apparent input capacitance of the tube, represented by the dotted condenser 256, is therefore fixed, and consequently an inductance 258 may be selected which will be naturally resonant in circuit, allowing for the effect of inductance 259, to a constant frequency lower than the working frequency range. The output circuit of the preceding automatically tuned amplifier includes the inductance 259 which is also selected to be naturally resonant in circuit, allowing for the effect of the inductance 258, to a constant frequency lower than the working frequency range, the overall natural capacitance in parallel therewith being indicated generally by the dotted condenser 257. Inductances 258 and 259 are not magnetically coupled together. They and the two resulting resonant circuits are coupled together through a coupling condenser 260 of relatively large magnitude so as to freely pass radio frequency energy from the output circuit of the preceding amplifier to the input circuit of the link stage, but which at the same time blocks the high direct anode potential of the preceding tube from reaching the control electrode of the link tube 252.

A complete receiver embodying our invention is illustrated in Fig. 6 of the drawings. This receiver comprises a suitable antenna circuit 60, the energy pick-up being fed to a sharply tuned

selector 62 having variable circuit constants. Selected energy of desired frequency is amplified in a plurality of automatically tuned amplifiers 64, 66 and 68. The selector and the automatically tuned amplifiers are connected in cascade by link circuits 70, 72 and 74, which may incidentally further amplify the selected energy. The radio frequency and modulation components are separated by means of a detector circuit 76, after which the modulation component may, if desired, be further amplified, and translated in any suitable reproducer.

For preventing reaction by the automatically tuned amplifiers on the selector we employ a link circuit 70 of a type which may be organized for better efficiency than that set forth in the copending application Serial No. 397,632, since issued as Patent 1,788,197, already mentioned, disclosing reactionless link means for preventing reaction by the amplifier on the selector. The present link circuit includes a screened grid tube 80, and the input circuit of the tube is connected to the last tune circuit, 82, of the selector, while the output circuit of the tube includes a transformer 84, the magnitude of which is selected to be automatically tuned by the input capacitance of the first tube in the automatically tuned amplifier 64. Transformer 84 is preferably bifilarly wound, and may consist of two sections wound in opposite directions in order to make the transformer astatic, in accordance with the patent to Lester L. Jones, No. 1,732,937 issued October 22, 1929.

Automatically tuned amplifier 64 may consist of a single amplifier stage or of a plurality of amplifier stages coupled directly in cascade and arranged to tune to different portions of the working frequency range.

It is coupled to automatically tuned amplifier 66 by means of a link circuit 72, which in this case has been illustrated as similar to that shown in Fig. 3, but which may be like that shown in Fig. 4 of the drawings. The input transformer 86 is selected to be naturally resonant in circuit to a frequency lower than the frequency range. It is preferably bifilarly wound in four alternately oppositely wound sections, in accordance with the copending application of Lester L. Jones, Serial No. 402,379, filed October 25, 1929, since issued as Patent 1,901,368, dated March 14, 1933. A series inductance 88 may be connected in series with the input circuit of the link tube, the inductance being of suitable magnitude to series resonate with the apparent input capacitance of the tube at the high frequency end of the range, like inductance 16 in Fig. 1, to which the inductance 88 corresponds both in location and in operation. The output transformer 90 is a bifilar astatic transformer of suitable magnitude to be automatically tuned by the input capacitance of the first tube in the amplifier 66.

Link circuit 74 is similar to that illustrated in Fig. 4, and includes a screened grid tube. The input transformer 92 is naturally resonant in circuit to a frequency lower than the working frequency range and is preferably bifilar and astatic in four sections, like transformer 86. An inductance 94 may be used for series resonating with the apparent input capacitance of the tube at the high frequencies. The output transformer 96 is selected to be automatically tuned by the input capacitance of the first tube in the amplifier 68.

The detector circuit 76 includes in its output a filter section 98 for separating the radio fre-

quency and modulation components of the rectified carrier. The resulting low impedance shunt for radio frequencies causes the input circuit of the detector tube to have a fixed input capacitance, and transformer 100 is selected to be naturally resonant in circuit therewith to a frequency lower than the working frequency range. A series inductance 102 may be used, as was explained in connection with Fig. 1.

10 It will be understood that while three automatically tuned amplifiers have been shown in the present case, less than three or more than three may readily be employed, depending upon the total gain desired in the amplifier. It will 15 also be understood that each of the automatically tuned amplifiers may consist of one or more stages, and that when more than one stage is used in each amplifier said stages may be cascaded directly together by tuning them to different portions of the frequency range. It will 20 further be understood that each of the automatically tuned amplifiers may have the same number of stages or different numbers of stages. For example, suppose there are two amplifiers 25 each consisting of a single stage, and that the total gain is slightly less than is desired, so that the addition of another link stage and another automatically tuned amplifier increases the total gain far more than is desired. In such case one 30 of the amplifiers may be made a two-stage amplifier, each stage being tuned over a portion of the frequency range.

In another case there might be two amplifiers each having two stages. For a slight increase in 35 overall gain one of the amplifiers may be made with three stages. For a further increase in overall gain both amplifiers might be made in three stages. For a still further increase in over-all gain both amplifiers may be made with two 40 stages and a third amplifier and link stage added.

Commercially successful, efficient, and stable automatically tuned amplifiers covering a broad frequency band may be made without the use of intermediate link stages, following the teachings 45 of the copending application Serial No. 397,633, since issued as Patent 1,779,881, aforesaid, but there is great difficulty when a considerable number of stages are to be used, and particularly when dealing with tubes having a relatively 50 high anode to cathode impedance, such as dry cell or battery tubes having a small power consumption. In Fig. 7 I have illustrated a six stage amplifier embodying my present invention and using battery type tubes, for example, tubes 55 having three volt thoriated tungsten straight filaments.

The amplifier is split into two sections, the first consisting of a pair of tubes T1 and T2 and the second consisting of the four tubes T3, T4, T5 and T6. The input and output circuits of tube T2 are related in an approximate way for automatic tuning, the input transformer L2 being held generally resonant to the received frequencies by the rising capacitance with decreasing frequency 60 of the input circuit of tube T2. The transformer L2 tunes very broadly, of course, due to the resistance R1 shunted across the primary thereof. The capacitance characteristic is made suitable for correcting the reaction characteristic of the 65 first tube, and it is primarily to best accommodate this use of tube T2 that the first section of the amplifier employs only a single automatically tuned stage. Resistance R1 is shunted by a small condenser C1 for further correction of the 70 reaction characteristic, these corrections all being 75

described in the copending application Serial No. 397,632, since issued as Patent 1,788,197, aforesaid. The output circuit of tube T3 is similar in nature to that of the first output circuit, producing a relatively low and constant 80 input capacitance in tube T3.

It is not necessary to have the same degree of refinement in the elimination of reaction on the input circuit of tube T3 as on the input circuit of tube T1. This is because the input circuit of tube T1 would usually be the last tuned circuit of a selector, which is a very sharply tuned circuit, whereas the input circuit of tube T3 is broadly tuned, and, therefore, not susceptible to slight reactions through tube T3. Because of this 85 the resistance R2 in the output circuit of tube T3 may be made of a different, and to increase the gain in tube T3, of preferably a higher value than that used for the output circuit of tube T1. It may be increased about two-fold, and a substantially proportionate increase also made in the magnitude of the coil L5.

This corresponding increase keeps the regenerative reaction due to the coil L5 substantially equal to the feed forward action of the resistance 100 R2. The total increase in the magnitude of the impedance of the output circuit of tube T3 is desirable in order to improve the gain therein, and the deviation from complete elimination of reaction over the frequency range is tolerable on account of the broad tuning characteristics of the input circuit of tube T3, as aforesaid. The capacitance in shunt with the resistance R1 may in the case of resistance R2 also be eliminated, since its function is to correct the reaction characteristic 105 to a degree of refinement which is unimportant in tube T3.

The inductance L4, included in series with the grid of tube T3, as in the case of the similar inductances in Fig. 6, series resonates with the 110 input capacitance of tube T3 at approximately the highest frequency of the band to be amplified.

The second section of the amplifier can best be considered starting back at the detector tube T7. This tube has a slightly smaller input capacitance 115 at radio frequencies than tube T3 because its output circuit is effectively shunted for radio frequency currents. In consequence both the transformer inductance L9 and the free grid section L10 are slightly larger than the corresponding elements in the input circuit of tube T3. The output circuit of tube T6 is arranged to give to tube 120 T6 an input capacitance characteristic suitable for tuning the input transformer L8. Transformer L8 is arranged to automatically tune transformer L7, and the latter is arranged to automatically 125 tune transformer L6, but this automatic tuning is over staggered portions of the frequency band, all as is described supra and in the copending application Serial No. 397,633, since issued as 130 Patent 1,779,881, previously mentioned.

The introduction of the reaction free link stage including tube T3 is extremely effective in smoothing out the gain curve of the complete amplifier. Also, the reaction characteristic of the whole 135 amplifier upon the selector is made more closely adherent to the normal desired reaction free characteristic, because the intermediate reaction free link circuit acts as a buffer against the transmission of reaction as well as capacitance changes 140 from the last amplifier stages back through to the first amplifier stage.

Suitable quantitative design constants are next given, assuming that the amplifier is intended to 145 operate over a frequency range of from about 500 150

- to 1500 kilocycles, and that battery tubes are to be used of the thoriated tungsten straight filament type, having a grid to plate capacitance of say 3 micro-microfarads, a tube conductance of say 650 micromhos measured with an anode potential of 90 volts and no grid bias other than that obtained by connecting the grid to the negative side of the filament, and an amplification factor of about 14. Resistance R1 may be 2800 ohms. Capacitance C1 is 20 micro-microfarads. Inductance L1 is 285 microhenrys. Transformer L2 is a bifilar transformer made astatic in two oppositely wound sections having a total inductance of 1.3 millihenrys.
- 15 The input capacitance of tube T3 with constants as given and with an anode potential of about 100 volts is of the order of 22 micro-microfarads. Inductance L4 is selected to series resonate with this input capacitance at a frequency of 1400 rather than 1500 kilocycles in order to better take advantage of the obtainable resonant rise in potential. The value of inductance L4 therefore is made 0.6 millihenrys. The inductance of transformer L3 together with the inductance L4 connected in series therewith should resonate in circuit with the input capacitance of tube T3 at about 550 kilocycles, but there is an appreciable capacitance in parallel with transformer L3 due to the plate to grid and filament capacitance of the preceding tube T2, which shunt capacitance alters the effective value of the inductance of the transformer L3. The effective inductance value should be proper for the desired parallel resonance, rather than the actual inductance value of transformer L3 when not connected in circuit. The value of L3 works out to be 2.77 millihenrys, obtained by a two section astatic bifilar wound transformer.
- Resistance R2 is 5600 ohms. Inductance L5 is 500 microhenrys. Transformer L6 is a bifilar transformer made astatic in two oppositely wound sections having a total inductance of 1.3 millihenrys. It should be noted that this value is effectively considerably reduced by the circuit R2, L5 connected in shunt therewith. Transformer L7 is a bifilar transformer made astatic by two oppositely wound sections having a total inductance of 0.72 millihenrys. Transformer L8 is a bifilar transformer made astatic in two oppositely wound sections having a total inductance of 0.86 millihenrys. Transformer L9 is a bifilar transformer made astatic in four alternately oppositely wound sections having a total inductance of 3.6 millihenrys. Coil L10 has an inductance of 0.75 millihenrys.
- 60 The bypass condensers C2, C3 and C4 are all about $\frac{1}{2}$ mfd. in capacitance, and are constructed for extremely low radio frequency impedance, in order to reduce distant stage feed back through common impedance in the B supply and filament circuits.
- 65 Attention is now directed to the amplifier a wiring diagram for which is given in Fig. 8. This amplifier employs screened grid tubes T1 and T3 for the link circuits. Tube T3 separates the amplifier into two automatically tuned sections, one of which has a single stage, T2, and the other of which has two stages, T4 and T5, this particular grouping of tubes having been selected in order to obtain a specified overall gain.
- 70 A selector is coupled to the input circuit of the screened grid tube T1. A radio frequency bypass condenser 110 is provided, the function of which is, in cooperation with the radio frequency choke 112, to prevent a radio frequency feed back
- from the amplifier to the selector through the cathode leads.
- 75 Transformers 114 and 116 are suitably related to obtain automatic tuning of the input circuit of tube T2. Inductance 118 is preferably connected in series with the control electrode of the screened-grid link tube T3 for reasons previously explained. Transformer 120 is automatically tuned over the higher frequency portion of the working frequency range by transformer 122, and the latter is automatically tuned over the lower frequency portion of the working frequency range by transformer 124. Inductance 126 is preferably connected in series with the control electrode of the detector T6, in a manner similar to that of inductance 118 of the link tube T3. It will be appreciated that the link tubes T1 and T3, while respectively used primarily to prevent reaction therethrough, and to obtain a constant apparent input capacitance suitable for automatic tuning, are nevertheless capable of providing and do provide considerable amplification gain, and serve a useful function as amplifier tubes alone, although in this respect their efficiency is perhaps less than might be obtainable were they designed primarily as amplifier tubes.
- 80 Design dimensions follow, assuming the tubes T1 and T3 to be alternating current screened grid tubes commercially designated type 224, and the tubes T2, T4 and T5 to be alternating current heater type tubes similar to those commercially designated as type 227, except that they have a greater amplification constant, say 12. Transformer 114 is a bifilar transformer made astatic in two oppositely wound sections having a total inductance of 0.81 millihenrys. Transformer 116 is a bifilar transformer made astatic in four alternately oppositely wound sections having a total inductance of 4.0 millihenrys. Inductance 118 is made astatic in two oppositely wound sections having a total inductance of one millihenry. Transformer 120 is a bifilar transformer made astatic in two oppositely wound sections having a total inductance of 0.72 millihenrys. Transformer 122 is a bifilar transformer made astatic in two oppositely wound sections having a total inductance of 1.39 millihenrys. Transformer 124 is a bifilar transformer made astatic in four alternately oppositely wound sections having a total inductance of 3.0 millihenrys. Inductance 126 is made astatic in two oppositely wound sections having a total inductance of one millihenry.
- 85 In general, it will be apparent from the foregoing description that by the use of our invention great freedom and flexibility is obtained in the design of automatically tuned amplifiers and in the design of radio receivers embodying the same. Any desired gain may be obtained while using automatic tuning over any desired range, and while retaining good efficiency and a relatively high gain per stage. Automatically tuned amplifiers may be cascaded indefinitely without excessive reaction and without limitation by reason of the particular frequency range to be amplified.
- 90 It will be apparent that while we have shown and described our invention in preferred forms, many changes and modifications may be made in the circuits disclosed without departing from the spirit of the invention, defined in the following claims. In many of these claims, we employ the term "link stage" or "link circuit", by which we mean merely a stage or circuit having primarily a linking or coupling function, although it may secondarily have other func-
- 95

tions. The claims do not rely on the word "link" for novelty, and include the same not by way of limitation, but solely for the convenience of the reader, in order to clarify and better fix in mind 6 the idea of the means comprehended by the claims.

In all of the claims reference is made to amplifiers which are "automatically tuned", by which we mean self-tuning amplifiers having physically 10 fixed circuit elements, in contradistinction to amplifiers having physically variable condensers or/and physically variable inductances. By "automatically tuned" we do not refer to that class of amplifier having variable condensers or coils 15 together with automatic mechanism for varying the same, but rather an amplifier of the class described in the foregoing specification and in the prior patents therein referred to.

We claim:

- 20 1. The combination with an automatically tuned radio frequency amplifier of an additional radio frequency amplifier stage coupled thereto and including a tube so arranged that the apparent input capacitance thereof is constant.
- 25 2. The combination with an automatically tuned radio frequency amplifier arranged to tune over a desired range of frequency of an additional radio frequency amplifier stage coupled thereto and so arranged that the input circuit 30 thereof is resonant to a constant frequency lower than the desired range of frequency.
- 35 3. The combination with an automatically tuned radio frequency amplifier of a screened grid tube coupled thereto and into which said amplifier works, said screened grid tube being arranged in circuit to act as an amplifier tube.
- 40 4. The combination with an automatically tuned radio frequency amplifier arranged to tune over a desired range of frequency of a screened grid tube having an input circuit coupled to said amplifier and resonant to a constant frequency lower than the desired range of frequency, into 45 which input circuit said amplifier works.
5. The combination with an automatically 50 tuned radio frequency amplifier of an additional radio frequency amplifier stage coupled thereto and comprising a tube having an input circuit into which said automatically tuned amplifier works, and an output circuit so arranged that the apparent input capacitance of the tube is kept 55 constant.
6. The combination with an automatically 60 tuned radio frequency amplifier arranged to tune over a desired range of frequency of an additional radio frequency amplifier stage coupled thereto and comprising a tube having an input circuit into which said automatically tuned amplifier works, and an output circuit so arranged that the apparent input capacitance of the tube 65 is kept constant, said input circuit being naturally resonant to a constant frequency lower than the desired range of frequency.
7. A radio circuit comprising an automatically 70 tuned amplifier, a second automatically tuned amplifier, and a link circuit for coupling the first and second amplifiers in cascade, said link circuit including a tube having a constant apparent input capacitance into which the first automatically tuned amplifier works.
- 75 8. A radio circuit comprising an automatically tuned amplifier arranged to tune over a desired range of frequency, a second automatically tuned amplifier arranged to tune over the same range of frequency, and a link circuit for coupling the first and second amplifiers in cas-

cade, said link circuit including a tube having a constant apparent input capacitance into which the first automatically tuned amplifier works.

9. A radio circuit comprising an automatically tuned amplifier arranged to tune over a desired range of frequency, a second automatically tuned amplifier arranged to tune over the same range of frequency, and a link circuit for coupling the first and second amplifiers in cascade, said link circuit having a tube and an input circuit therefor naturally resonant to a constant frequency lower than the desired range of frequency, into which input circuit the first automatically tuned amplifier works. 80

10. A radio circuit comprising an automatically tuned amplifier, a second automatically tuned amplifier, and a link circuit for coupling the first and second amplifiers in cascade, said link circuit including a screened grid tube. 85

11. A radio circuit comprising an automatically tuned amplifier arranged to tune over a desired range of frequency, a second automatically tuned amplifier arranged to tune over the same range of frequency, and a link circuit for coupling the first and second amplifiers in cascade, said link circuit including a screened grid tube. 90

12. A radio circuit comprising an automatically tuned amplifier arranged to tune over a desired range of frequency, a second automatically tuned amplifier arranged to tune over the same range of frequency, and a link circuit including a screened grid tube having an input circuit naturally resonant to a constant frequency lower than the desired range of frequency, into which input circuit the first amplifier works. 105

13. A radio circuit comprising an automatically tuned amplifier, a second automatically tuned amplifier, and a link circuit for coupling the first and second amplifiers in cascade, said link circuit including a tube having an input circuit into

which the first automatically tuned amplifier works, and an output circuit so arranged as to cause the tube to have a constant apparent input 110

capacitance. 115

14. A radio circuit comprising an automatically tuned amplifier arranged to tune over a desired range of frequency, a second automatically tuned amplifier arranged to tune over the same range of frequency, and a link circuit for coupling the first and second amplifiers in cascade, said link circuit including a tube having an input circuit into

which the first automatically tuned amplifier works, and an output circuit so arranged as to cause the tube to have a constant apparent input 120

capacitance. 125

15. A radio circuit comprising an automatically tuned amplifier arranged to tune over a desired range of frequency, a second automatically tuned amplifier arranged to tune over the same range of frequency, and a link circuit for coupling the first and second amplifiers in cascade, said link circuit including a tube having an input circuit into

which the first automatically tuned amplifier works, and an output circuit so arranged as to cause the tube to have a constant apparent input 130

capacitance. 135

16. A radio circuit comprising a sharply tuned selector including a plurality of resonant circuits coupled directly in cascade and having variable circuit constants, a radio frequency amplifier including a plurality of stages coupled in cascade 140

145

17. A radio circuit comprising a sharply tuned selector including a plurality of resonant circuits coupled directly in cascade and having variable circuit constants, a radio frequency amplifier including a plurality of stages coupled in cascade 150

and having fixed circuit constants, and a link circuit for coupling the amplifier to the selector, said link circuit including screened grid tube for preventing reaction by the amplifier on the selector.

5 17. A radio circuit comprising a selector having variable circuit constants, an automatically tuned radio frequency amplifier having fixed circuit constants, and a link circuit for coupling the automatically tuned amplifier to the selector, said
10 link circuit including a screened grid tube for preventing undesired reaction by the automatically tuned amplifier on the selector.

15 18. A radio circuit comprising a selector having variable circuit constants, a plurality of automatically tuned amplifiers having fixed circuit constants, and a plurality of link circuits connecting the selector and the automatically tuned amplifiers in cascade, said link circuits each including a tube arranged to have a constant ap-
20 parent input capacitance into which the preceding circuit works.

19. A radio circuit comprising a selector having variable circuit constants, a plurality of automatically tuned amplifiers having fixed circuit constants arranged to tune over the same frequency range, and a plurality of link circuits connecting the selector and the automatically tuned amplifiers in cascade, said link circuits each including a tube arranged to have a constant ap-
25 parent input capacitance into which the preceding circuit works.

20. A radio circuit comprising a selector having variable circuit constants, a plurality of automatically tuned amplifiers having fixed circuit constants arranged to tune over the same desired frequency range, and a plurality of link circuits connecting the selector and the automatically

tuned amplifiers in cascade, said link circuits each including a tube arranged to have a constant apparent input capacitance into which the preceding circuit works, the last tuned circuit of the selector acting as the input circuit of the first link circuit, and the input circuits of the remaining link circuits being resonant to a constant frequency lower than the desired range of frequency.

21. A radio circuit comprising a selector having variable circuit constants, a plurality of automatically tuned amplifiers having fixed circuit constants, and a plurality of link circuits for coupling the selector and the amplifiers in cascade, said link circuits including screened grid tubes.

22. A radio circuit comprising a selector having variable circuit constants, a plurality of automatically tuned amplifiers having fixed circuit constants and arranged to tune over the same frequency range, and a plurality of link circuits for coupling the selector and the amplifiers in cascade, said link circuits including screened grid tubes.

23. A radio circuit comprising a selector having variable circuit constants, a plurality of automatically tuned amplifiers having fixed circuit constants and arranged to tune over the same desired frequency range, and a plurality of link circuits for coupling the selector and the amplifiers in cascade, said link circuits including screened grid tubes, the last tuned circuit of the selector acting as the input circuit of the first screened grid tube, and the input circuits of the remaining screen grid tubes being naturally resonant to a constant frequency lower than the desired range of frequency.
